UNITED STATES PATENT OFFICE.

ELIHU C. WILSON, OF LOS ANGELES, CALIFORNIA

PUMP.

Application filed July 3, 1922. Serial No. 572,547.

To all whom it may concern:

Be it known that I, ELIHU C. WILSON, a citizen of the United States, residing in Los Angeles, county of Los Angeles, State 5 of California, have invented new and useful Improvements in Pumps, of which the following is a specification.

This invention has to do with pumps and particularly well pumps, and it is an object 10 of the invention to provide improvements in devices of this character which will render them particularly effective, convenient to handle and repair, and commercially practical.

15 This application is a continuation in part of my application for Letters Patent for an improvement in pump, filed Sept. 27, 1916, Ser. No. 122,515, renewed Jan. 23, 1921, as application Ser. No. 479,944.

20 Well pumps, generally, are subject to severe operating conditions, that is, they are handled roughly, are used to handle fluid that is dirty or which carries materials detrimental to the pump parts, etc., and therefore require frequent inspection and repair.

25 The foreign materials such as sand, and the like carried by the fluid being pumped is particularly detrimental to the working parts of the pump, for instance, the valves, 30 and the plunger and its cooperating part or parts, as the case may be. To inspect or repair a part it is necessary to remove it from the well, which operation ordinarily requires removal of the pump casing and the

35 sucker rods and is therefore troublesome and costly. The amount of time and labor involved in removing and replacing the pump or the necessary parts, depends upon the type and design of pump. Heretofore effort

40 has been made to simplify these operations but in most cases have been at the sacrifice of features of operation and have been operatively impractical for one reason or another.

45 This invention provides a pump which, when placed in the well, will operate effectively, which can be arranged in and removed from the well in a particularly simple manner, and which is simple in construction

50 and operatively practical. In accordance with the invention all of the working parts of the pump can be placed in and removed from the well by handling only the sucker rods, or an equivalent part, and the several

55 parts can be seated in manners particularly suited to withstand the conditions under

which they operate. In other words, the construction and arrangement provided by the present invention is such that the foot valve and working barrel, which are the 60 parts that are removably seated in position, are seated so that the barrel, which is the one most subject to being dislodged from its seat during operation, is seated more securely or positively than the foot valve. 65

The various objects and features of the invention will be best and more fully understood from the following detailed description of a typical embodiment of the invention, throughout which reference is had to 70 the accompanying drawings in which—

Fig. 1 is a vertical detailed sectional view of a typical type of pump embodying the present invention; Fig. 2 is a fragmentary elevation of certain of the removable parts 75 of the pump; Fig. 3 is a somewhat enlarged transverse detailed sectional view taken as indicated by line 3—3 on Fig. 1; Fig. 4 is a view similar to Fig. 3 taken as indicated by line 4—4 on Fig. 1; Fig. 5 is a view similar 80 to Fig. 3 taken as indicated by line 5—5 on Fig. 1; and Fig. 6 is a view similar to Fig. 3 taken as indicated by line 6—6 on Fig. 1.

The particular pump which I here set forth for the purpose of facilitating a clear 85 understanding of the present invention, comprises, generally, a stationary, or at least relatively stationary, discharge pipe or tubing 10, a stationary suction pipe 11 attached to the lower end of the discharge 90 pipe 10, a working barrel 12 removably mounted or seated in the stationary part, a plunger 13 arranged to reciprocate in the barrel 12, an operating or "sucker" rod 14 attached to the plunger and extending therefrom upwardly to the top of the well, a foot valve 15 removably mounted or seated in a stationary part, a working valve 32 carried by the moving parts, being arranged between plunger 13 and sucker rod 14, and a 100 link or connecting rod 16 which connects the plunger and foot valve in such a manner as to allow the plunger its pumping movement and to pull the standing valve out when the plunger is pulled above its working stroke. 105

The discharge pipe 10, which serves to conduct the pumped fluid from the pump to the top of the well, may comprise a plurality of sections 17 of tubing or casing of a 110 suitable size, connected by collars 18. The suction pipe 11 being stationary, like the

2
 discharge pipe 10, is preferably attached to the lower end of the discharge pipe 10. In the particular form of construction shown in the drawings the suction pipe 11 is connected with the discharge pipe 10 through a collar 19. The collar 19 is attached to the lower end of the discharge pipe 10 by a suitable coupling 20 while the upper end of the suction pipe 11 is connected with the end of the collar 19 by a suitable coupling 21. The collar 19 is formed with a central seat opening 22 which tapers or converges downwardly. The conical face of opening 22 is preferably finished and will hereinafter be termed the working valve seat. Parts 19, 20 and 21 may well be made integral if desired.

The working barrel 12 is a comparatively long cylindrical member through which the plunger 13 extends. The particular pump disclosed in the drawings being a packed pump (although that is not at all necessary) the working barrel 12 is made to fit the plunger loosely and packing 24 is arranged in the annular space between the plunger and the working barrel. The particular packing 24 illustrated in the drawings is carried by the plunger 13 between a collar 14^a set on the plunger by a pin 14^c, and a collar 14^b screw threaded on the plunger and set in position by a set screw 14^a. The packing is divided into two parts, one adjacent each collar, and a compression spring 14^e is carried around the plunger between two parts of the packing, as clearly illustrated in Fig. 2 of the drawings. In operation the collar 14^b is screw threaded on the plunger until the spring 14^e is compressed the desired amount whereupon it is set by the set screw 14^a. If so desired, the collar 14^b may be set in position by a locking collar 14^f, as I have illustrated in the drawings. The spring 14^e bears against the two parts of the packing so that they maintain a tight joint between the plunger and working barrel.

A seating part 25 is attached to the lower end of the working barrel 12 so that it is, operatively, a continuation of the working barrel. The seating part 25 is formed with a central bore or opening 26 which freely passes the plunger 13. The outer part of the seating part 25 tapers correspondingly to the angle of the conical seat 22 and is preferably formed with a recess 30 for carrying Babbit metal, leather washers, or other packing material 31 to form a tight joint between the working barrel and collar.

The plunger 13 is a comparatively long tubular member extending downwardly through the working barrel and into the suction pipe 11. The plunger 13 is connected through working valve 32 to the sucker rod 14, which in the particular form of pump under consideration, is a solid rod. The working valve 32 illustrated in the

drawings is of typical construction and operation and comprises, generally, a cage 33 which screw threads into the upper end of the plunger 13, and a ball 34 which is adapted to work in the cage 33 and to cooperate with a seat 35 in the cage 33 to control the opening 36 formed through the cage 33. It is to be particularly noted that the cage 33 of the valve 32 is formed with a flange 37 of larger diameter than the plunger so that it will engage the collar 13^a carried by the upper end of the barrel 12 when the plunger is lowered sufficiently.

The foot valve 15 is removably carried at the lower end of the suction pipe 11 by a carrier 38 attached to the lower end of the suction pipe 11 by a coupling 39^a, so that the carrier is practically a continuation of the suction pipe 11. In the particular form of construction shown in the drawings the carrier 38 is formed with a central opening 39 which tapers downwardly forming the foot valve seat. The foot valve 15 may be of typical construction and operation and may comprise a body part 41^a having an opening 41^b through it and a seat 41^c at the upper end of the opening, a cage 41 attached to the upper end of the body 41^a and a ball 41^e carried in the cage 41 to cooperate with the seat 41^c. The body 41^a of the valve 15 has a seating part 45 which tapers downwardly at an angle corresponding to the angle of the seat 39 which part is preferably recessed to carry Babbit metal, leather washers, or other packing material 100 46 to form a tight joint with the seat 39.

The rod 16, commonly known in the art as a "Garbutt" rod, is attached to cage 41 of foot valve 15 and extends upwardly therefrom through opening 48 in a bushing 49 attached to the lower end of the plunger 13. The rod 15 extends loosely through the opening 48 in the stop 49 and is provided at its upper end, within the plunger 13, with a head 50 which will not pass through the opening 48. The bushing 49 is of such size and configuration as to engage the lower end of the barrel part 25 when the plunger is raised a sufficient amount. It may be here pointed out that the rod 16 is long enough to allow the normal pumping stroke of the plunger without raising the foot valve. A spring 52 surrounds coupling rod 16 and forms the resilient means by which the foot valve is pressed into its seat when the plunger is lowered to a point below the lower end of its pumping stroke.

The operation and handling of the pump is as follows: The discharge pipe 10, the collar 19, the suction pipe 11, and the carriers 38, which are the relatively stationary parts of the pump mechanism, are fixed in the well at the desired depth. It may be here stated that the parts just described, may be considered as forming or comprising a carrier 130

or frame structure for the removable or working parts hereinafter mentioned. The removable parts, namely the working barrel 12, the plunger 13, the working valve 32, the spring 52 the rod 16, and the foot valve 15, are lowered into the discharge pipe 10 by lowering the sucker rods in the well known manner. Upon the removable parts nearing operative position the seating parts 45 and 25 engage the seats 40 and 23 respectively. To set the parts in operative position the sucker rod 13 is lowered further until the flange 37 engages the collar 13^a to drive the working barrel tight into the seat 23. In the meantime, bushing 49 has compressed spring 52 and has resiliently pressed the standing valve into its seat by the time the working barrel has been pressed positively into its seat by collar 37 striking its upper end. The spring 52 is particularly desirable in this particular location, that is between the plunger and foot valve 15 rather than between the plunger and the working barrel because it not only causes proper seating of the parts and compensates for inaccuracies in construction and arrangements of parts, but also causes the working barrel to be seated somewhat more tightly and positively than the foot valve 15. In practice, it has been found that it is particularly desirable that the working barrel be seated more tightly than the foot valve 15 as there is more tendency for the working barrel to work loose and become dislodged from its seat than there is for the foot valve to work loose and become dislodged from its seat. After the movable parts are seated in a manner such as I have just described, the plunger can be raised somewhat and then reciprocated for pumping action. In this pumping action flange 37 does not necessarily strike the upper end of the working barrel; and neither is spring 52 necessarily struck at the lower end of the plunger stroke. When it becomes desirable to remove the working parts of the pump for inspection or repair, the sucker rod 14 is drawn upwardly so that the bushing 49 engages the lower end of the barrel seat part 25 and lifts the barrel while the head 50 of rod 16 is engaged by the bushing 49 so that the foot valve 15 is lifted out of the carrier 38. The working or removable parts may then be easily withdrawn from the well by simply pulling the sucker rods. In practice it may be desirable to so proportion or construct the various parts of the pump to cause one of the removable parts to be dislodged from its seat before the other; so that it is only necessary to pull the sucker rod 14 upwardly with sufficient force to dislodge one of the parts at a time. This may be easily effected by making rod 16 longer or shorter, as desired.

As the present invention is confined more

particularly to the arrangement of parts for effecting the particular seating action hereinabove described it is to be understood that I do not limit myself to other details hereinabove recited but wish to reserve to myself any changes or variations that may appear to those skilled in the art and fall within the scope of the following claims.

The application before mentioned, of which this is a continuation, was co-pending with another application for pump, Ser. No. 78,625, filed Feb. 16, 1916, and which eventually in Letters Patent No. 1,299,083, dated April 1, 1919. In said application and patent the broader claims are generic to both the specific form there shown; while the claims of this present application are directed to the form here shown. In said patent there is described and claimed a structure generally similar to that here shown, and with the same operative functions of seating the two parts (barrel and standing valve) through the intervention of a spring in one case; but specifically, the spring in the patent is shown as applied to the barrel, where as here it is shown and claimed only as applied to the working valve.

Having described a preferred form of my invention, I claim:

1. In a pump of the character described, a stationary structure providing two seats, a barrel adapted to be removably carried on one of said seats, a valve adapted to be removably carried on the other seat, a plunger carried and adapted to reciprocate in the barrel, and means for simultaneously positively forcing the barrel to its seat and yieldingly forcing the valve to its seat.

2. In a pump of the character described, a stationary structure providing two seats, a barrel adapted to be removably carried by one seat, a foot valve adapted to be carried by the other seat, a plunger carried and adapted to reciprocate in the barrel, means loosely connecting the plunger and foot valve, yielding means between the plunger and foot valve through which the foot valve is forced to its seat, and means in connection with the plunger for forcing the barrel to its seat.

3. In a pump of the character described, a stationary structure providing two seats, a barrel adapted to be removably carried by one of the seats, a foot valve adapted to be removably carried by the other seat, a removable plunger operating in the barrel; a part in connection with the plunger for engaging the barrel to force it positively to its seat, a part in connection with the plunger to engage the barrel to remove it from its seat, and a spring between the plunger and foot valve adapted to be actuated by the plunger to yieldingly force the valve to its seat.

4. In a pump of the character described, a

stationary structure having superposed seats, a removable barrel having a seating part adapted to engage the upper seat, a plunger slidable through the barrel, a foot valve loosely connected to the lower end of the plunger and adapted to engage the lower seat, yielding means arranged to force the foot valve to its seat upon lowering of the plunger below a predetermined position, and 10 means in connection with the plunger for engaging the barrel so that it is removed when the plunger is removed.

5. In a pump, a working barrel, a plunger adapted to reciprocate in the barrel, there 15 being a seat in the pump for the barrel, and means upon the plunger for forcing said barrel into position upon its seat upon the lowering of said plunger; in combination with a foot valve loosely connected with the plunger 20 and yielding means between the plunger and the foot valve, there being a seat for the foot valve to which the foot valve is applied through the agency of said yielding means.

6. In a pump, a casing provided with a 25 seat, a barrel fitted within the casing, a plunger slidable through the barrel, a foot valve loosely connected to the plunger and adapted to engage the seat, yielding means actuated by the plunger on its lowering to

force the foot valve in position upon its 30 seat.

7. In a pump, a working barrel, a seat in the pump therefor, a plunger, packing means between the barrel and the plunger and removable with the barrel and the plunger, a 35 seat in the pump for the barrel, a foot valve loosely connected with the plunger, a seat for the foot valve, and two separate means whereby the plunger acts to force said barrel and said foot valve to the respective 40 seats; the said means acting on the foot valve being a yielding means.

8. In a pump, a working barrel, a seat in the pump therefor, a plunger, packing means between the barrel and the plunger and removable with the barrel and the plunger, a 45 seat in the pump for the barrel, a foot valve loosely connected with the plunger, a seat for the foot valve, and separate means whereby the plunger acts to force said barrel and said 50 foot valve to the respective seats; one of said last named means acting in a yielding manner and comprising a spring interposed between the plunger and the foot valve.

In witness that I claim the foregoing I 55 have hereunto subscribed my name this 26th day of June, 1922.

ELIHU C. WILSON.
